UNITED STATES PATENT OFFICE.

EDWARD L. MEGILL, OF NEW YORK, N. Y.

GAUGE PIN.

1,408,756.

Specification of Letters Patent.

Patented Mar. 7, 1922.

Application filed August 11, 1919. Serial No. 316,925.

To all whom it may concern:

Be it known that I, EDWARD L. MEGILL, a citizen of the United States, residing at New York, in the county of New York and State of New York, have invented certain new and useful Improvements in Gauge Pins, of which the following is a specification.

This invention relates to improvements in gauge pins which are adapted to be removably secured on a tympan, and one of the objects of the invention is to provide a device of this sort in which there is a prong which penetrates through and underlies the tympan sheet, a head portion which acts as a stop for sheets fed into the press, presser arms which overlie the tympan sheet and cooperate with the prong, and with teeth on the lower edge of the head to hold the device in position on the tympan, and a spring tongue extending forwardly of the head to prevent the vertical displacement of sheets which have been fed up to the head, all of these parts being integrally formed from a single piece of metal.

Another object of the invention is to provide presser arms extending backwardly from the head, of such shape and so disposed that when the pin is inserted in the tympan sheet wrinkling and tearing of the sheet will be prevented.

A further object is to so relate the forwardly extending spring tongue to the head of the pin in such manner that whereas the head may be quite low in its vertical aspect, and the spring tongue high above the tympan at its outer end, the inner end or root of the spring tongue will be desirably low and close to the tympan.

Other objects and aims of the invention, more or less broad than those stated above, together with the advantages inherent, will be in part obviously and in part specifically referred to in the course of the following description of the elements, combinations, arrangements of parts, and applications of principles constituting the invention; and the scope of protection contemplated will appear from the claims.

In the accompanying drawings, which are to be taken as part of this specification, and in which I have shown merely a preferred form of embodiment of the invention, Figure 1 is a plan view showing a device made in accordance with my invention as applied to a tympan; Figure 2 is an edge view of

the same; Figure 3 is a perspective view of the gauge pin looking from the rear; Figure 4 is a view similar to Figure 3 but looking at the front of the device; Figure 5 is a view of the blank from which the pin is formed up.

Referring to the numerals on the drawing and particularly to Figure 5, there is shown a blank comprising a body portion 6 having rearwardly extending divergent presser-arm portions 7, with rounded ends 8. Between these arms and also extending rearwardly from the body portion 6 is a holding prong portion 9. From about midway of the other edge of the body portion 6 extends a spring tongue portion 10, and it will be observed that the material of this edge portion is cut out as indicated at 11 on either side of the spring tongue portion to facilitate the bending of the front head portions 12 on either side of the tongue 10 as hereinafter described. The extreme ends of this edge portion are formed with tooth like members 14, which are pressed down into the tympan sheet when the device has been brought to proper position thereon. The body portion 6 is formed up as shown in Figures 1 to 4 inclusive, by bending it along lines indicated in dot in Figure 5, the portion of the body between the left-hand dotted line indicated at 15 and the forward edge of the body portion being bent downwardly, and the portion between the rearward edge of the body portion and the adjacent dotted line 16 being also bent downwardly, leaving the portion of the head between the lines 15 and 16 as the top or connecting member of an inverted U, with the arms 7 and the holding prong 9 extending in a common horizontal plane. The teeth 14 on the forward, and now vertical, portion of the U-shaped head are of such length that they will extend below the plane of the arms 7, whereas the prong tongue portion 10, by reason of the cut-outs 11 in the forward edge of the body 6 will have its root extending from the forward vertical head portion above the plane of the arms 7, the relative height of the root of the tongue depending of course upon the depth of the cuts 11. The tongue portion 10 is given a bend substantially as shown in Figure 2, that is to say the portion nearest the root bends downwardly and then the tongue bends upwardly again so that its outer end is comparatively high. Thus I

obtain a spring tongue with a high outer

end and a low inner end and extending from a gauge pin with a desirably low head.

The device thus described lends itself readily to the ordinary shop practice which is followed in the manufacture of articles of this sort and has the advantage of providing an integral construction in which are found all the necessary elements, as head member, holding prong, presser arm and spring tongue, so related that the prong may be readily pushed into the tympan, and the head tapers to bring its teeth into holding engagement with the tympan sheet when the desired position is reached; while the divergent presser arms with their rounded ends pass smoothly over the face of the tympan and spread out the wrinkles therein and avoid tearing of the paper as the pin is pushed to position. Obviously tearing through would occur if the arms were spaced parallel with the prong and did not have the rounded or curved ends.

The tongue is made integral with the head of the gauge pin and in line with the prong, and tapers from the root towards the tip and curves upwardly to the outer end, so that when in use on the press and coming in contact with high furniture, slugs, quads or patent bases in the form, the tongue will yield elastically in co-action with the yielding of the prong, and thereafter return to its normal height in relation to the tympan to which it is attached. By reason of this inherent elasticity of the device, when any pressure comes on the end of the spring tongue the device as a whole will yield without breaking, pivoting slightly on the teeth 14. The curving of the spring tongue is to give it greater height than is afforded by the gauge pin proper. The object of this is that the sheets may be fed low against the tympan, and yet be sufficiently high at the end of the tongue for the sheets to catch under when being fed to the low gauge head. The gauge head itself being an unyielding structure is desirably low so that it does not come in contact with the hard substances in the chase around the type, consisting of the above-mentioned quads etc. Of course compression is not calculated upon beyond that allowed by the gauge head, which is formed to a very slight height, say one-sixteenths of an inch, as that has been determined as the necessary height for the safe feeding of the sheets. Since, however, sheets would be likely to

pass over such a low gauge in being fed onto the platen, the extra height necessary is obtained by the upturned end of the tongue extending from the gauge head as described. The down bend of the tongue adjacent its root keeps the sheets from feeding above the flat surface of the head onto the rounded corners thereof. This drop is an advantage in the manufacturing of the article because allowance may be made for different thicknesses of stock, card-board or paper which is to be fed against the vertical head portion and between the tympan sheet and the root of the tongue.

It will be understood that primarily this device is an improved low gauge pin, that is low at the head so that it is adapted to narrow spaces between high bases of printing plates, with a tongue of sufficient flexibility to prevent breakage and of sufficient height at its outer end to prevent mis-feeding.

I claim:

1. A gauge pin having a head or stop portion presenting a flat face with a top and a bottom edge, cooperating clamping members extending in a common plane substantially at right angles and rearwardly from the bottom edge, and an integral tongue extending forwardly from the top of the head portion, the head portion being included between and spacing apart the plane of the clamping members and any parallel plane in which lies any part of the tongue.

2. A device as set forth in claim 4, in which the inner end portion of the tongue is bent towards the plane of the clamping members, and the outer end portion of the tongue is bent away from that plane.

3. A gauge pin comprising a head of inverted U-shape, the forward vertical wall of the head presenting a flat face and being provided with teeth on its lower edge at the end and cut out adjacent each tooth, a tongue extending forwardly and upwardly from the upper edge portion of said wall and having its root defined between the cut-outs therein, divergent presser arms with rounded ends extending rearwardly from the lower edge of the rear vertical wall, and an integral holding prong extending rearwardly from the lower edge of said wall between the arms and in the plane of the arms.

In testimony whereof I affix my signature.

EDWARD L. MEGILL.
